UNITED STATES PATENT OFFICE.

WILLIAM C. RUST, OF GOLDDENDALE, WASHINGTON.

CLIP.

1,316,189.

Specification of Letters Patent. Patented Sept. 16, 1919.

Application filed January 27, 1919. Serial No. 273,351.

To all whom it may concern:

Be it known that I, WILLIAM C. RUST, a citizen of the United States, residing at Goldendale, in the county of Klickitat and 5 State of Washington, have invented certain new and useful Improvements in Clips, of which the following is a specification, reference being had to the accompanying drawings.

10 This invention relates to certain improvements in clips, and has relation more particularly to a device of this general character for retaining articles within a pocket, and it is an object of the invention to provide a device of this general character having novel and improved means whereby the same serves effectively to prevent articles falling from the pocket, and particularly when the user is in a stooping position.

20 It is also an object of the invention to provide a novel and improved clip of this type which may be employed with facility and convenience in connection with pencils, fountain pens, pocket combs, or the like, and 25 wherein a specially designed holder is provided when the clip is employed in connection with a comb.

The invention consists in the details of construction and in the combination and arrangement of the several parts of my improved clip whereby certain important advantages are attained and the device rendered simpler, less expensive and otherwise more convenient and advantageous for use, 35 as will be hereinafter more fully set forth.

The novel features of my invention will hereinafter be definitely claimed.

In order that my invention may be the better understood, I will now proceed to 40 describe the same with reference to the accompanying drawings, wherein:

Figure 1 is a view in elevation illustrating a clip constructed in accordance with an embodiment of my invention and applied to 45 a comb, together with a holder in which the comb is inserted;

Fig. 2 is a view in edge elevation of the structure as illustrated in Fig. 1;

Fig. 3 is a view in perspective of my improved clip as illustrated in Figs. 1 and 50 2; and

Fig. 4 is a view in perspective illustrating a clip constructed in accordance with a further embodiment of my invention, and 55 particularly adapted for use in connection with a pencil, fountain pen, or the like.

As is particularly illustrated in Figs. 1, 2, and 3, C denotes a comb adapted to be inserted within a holder H or the like, and which holder has a side face at its open or 60 entrance end cut away as indicated at 1.

Each side face of the back 2 of the comb is provided with a longitudinally disposed groove or channel 3 in which is adapted to be engaged a spring jaw 4 of the body B of 65 my improved clip.

The body B is substantially U-shaped in cross section and is adapted to straddle the back of the comb or the like so that the spring jaws 4 thereof may readily engage 70 within each of the grooves 3 so that an effective engagement will be had with the comb.

The lower end of one of the jaws 4 is provided with an outstanding lateral extension 75 5 having its outer extremity rounded as at 6 in a direction away from the body B and which rounded portion is continued by an extended resilient tongue 7. The tongue 7 is doubled back upon itself as indicated at 7^a 80 and said returned portion 7^a is provided with a rounded part 8 which overlies and snugly contacts with the rounded portion 6 of the extension 5 hereinafter referred to. The rounded portion or part 8 terminates 85 in the outwardly directed finger-piece 9 inclined in a direction away from the body B.

The returned portion 7^a adjacent the rounded part or portion 8 is provided with the oppositely directed prongs or projections 10 which are bent to overlie and contact with the outer face of the tongue 7 adjacent the curved portion or part 6 whereby the tongue 7 and the returned portion 7^a thereof are held in properly assembled relation and the finger-piece 9 is anchored in 95 a manner to facilitate its function.

The connected extremities of the tongue 7 and the returned portion 7^a thereof are engaged within or otherwise secured to an engaging member 11 preferably a spherical body, and which member 11 is adapted, through the inherent resiliency of the tongue 7 and the returned portion 7^a to afford an effective clamping means for maintaining the clip in the article with which the clip is engaged in applied position such as within the holder H or within the pocket.

When it is desired to remove the article, such as the comb C, it is only necessary to 110 press inwardly on the finger-piece 9 to release the member 11 of its clamping action.

- In the form of invention illustrated in Figs. 1 to 3 inclusive, the extension 5 is disposed outwardly and laterally relative to a jaw 4 of the body B, but when the clip is 5 adapted for use in connection with a pencil, fountain pen, or the like, the extension 5^a is as is particularly illustrated in Fig. 4 extends outwardly and laterally from an end portion of the central part of the body B'. 10 The form of my invention as disclosed in Fig. 4 is otherwise the same as has hereinbefore been described and for which reason similar parts are identified by the same reference characters. 15 When my device is employed in connection with the holder H it will also be understood that the member 11 is adapted to engage in a conventional manner a wall of the pocket so that in addition to maintaining 20 the comb C within the holder H, the holder H will be effectively held within the pocket. From the foregoing description, it is 25 thought to be obvious that a clip constructed in accordance with my invention is particularly well adapted for use by reason of the convenience and facility with which it may be assembled and operated, and it will also be obvious that my invention is susceptible of some change and modification without 30 departing from the principles and spirit thereof, and for this reason I do not wish to be understood as limiting myself to the precise arrangement and formation of the

several parts herein shown in carrying out my invention in practice except as herein- 35 after claimed.

I claim:

1. A clip of the class described comprising a body provided with engaging jaws, a lateral extension carried by said body continued by a resilient tongue, said tongue comprising two overlying portions connected at their outer extremities, the inner extremity of one of said portions partially overlying the extension and continued by 45 an outstanding finger-piece.

2. A clip of the class described comprising a body provided with engaging jaws, a lateral extension carried by said body continued by a resilient tongue, said tongue 50 comprising two overlying portions connected at their outer extremities, the inner extremity of one of said portions partially overlying the extension and continued by an outstanding finger-piece, said portion adjacent its inner end being provided with 55 prongs overlying the second portion of the tongue for holding said overlying portions against relative movement.

In testimony whereof I hereunto affix my 60 signature in the presence of two witnesses.

WILLIAM C. RUST.
